United States Patent Office.

O. W. ALGER, OF RICHMOND, VERMONT.

Letters Patent No. 66,275, dated July 2, 1867.

IMPROVED WASHING MACHINE.

The Schedule referred to in these Letters Patent and making part of the same.

TO ALL WHOM IT MAY CONCERN:

Be it known that I, O. W. ALGER, of Richmond, Chittenden county, and State of Vermont, have invented a new and improved Washing Machine; and I do hereby declare the following to be a full and exact description of the same, reference being had to the accompanying drawings, which are made part of this specification, and in which the figure is a perspective view.

This consists of two hinged portions, a box with a ribbed bottom, and a lid with a ribbed under surface. Between the ribs of the box are perforation through which water passes to and fro, as the lid is raised and depressed. In the drawings—

A is the frame of the machine, and rests with its lower end upon the bottom of the wash-tub which is partly filled with suds, and with its lower surface against the side so as to have an inclined position. The inside of the bottom of the box has cleats *a a*, and rows of holes between the cleats. The upper end B is secured in the cheeks C by the pivoted bar D, and, being hinged therein, is capable of being lowered as seen in red lines. The hinged lid E has a handle, F, and is capable of motion on the pivots G.

The action is as follows: When the handle is lifted, the tendency to produce a vacuum beneath causes the water to be forced through the perforations of the bottom, thus raising the clothes from the lower ribbed surface, leaving a stratum of water underneath the cloth, and keeping the cloth in contact with the upper ribbed surface until the latter is elevated above the side and end boards, when the water will flow in between the lid and the clothes. When the handle is depressed the cloth is between two strata of water. The upper stratum is forced through the fabric and both strata through the perforations. A firm squeeze is given to the clothes by the two opposing ribbed surfaces. The reciprocating action is continued, alternately flowing the water against and around the clothes and forcing it through and out of them.

Having described my invention, what I claim as new, and desire to secure by Letters Patent, is—

The arrangement of the box A with ribs and perforations, and the ribbed and hinged lid, operating substantially as described.

O. W. ALGER.
